UNITED STATES PATENT OFFICE.

FRANK E. FARNHAM, OF PROVIDENCE, RHODE ISLAND.

CUFF-PIN.

No. 841,772.

Specification of Letters Patent.

Patented Jan. 22, 1907.

Application filed April 6, 1906. Serial No. 310,361.

To all whom it may concern:

Be it known that I, FRANK E. FARNHAM, a citizen of the United States, residing at Providence, in the county of Providence and State of Rhode Island, have invented certain new and useful Improvements in Cuff-Pins, of which the following is a specification, reference being had therein to the accompanying drawings.

10 Like letters indicate like parts.

Figure 1 is a top plan of a sheet of metal cupped up and cut to form the blank for the front or ornamental portion of my improved cuff-pin. Fig. 2 is a top plan view of the blank so formed and cut. Fig. 3 is a side elevation of said blank after its side flanges and pointed ends have been turned up. Fig. 4 is a side elevation of the pin-tongue. Fig. 5 is a top plan view of the lining-plate with the 15 pin-catch and the earpieces bent up. Fig. 6 is a side elevation of the same. Fig. 7 is a view of my improved cuff-pin as seen partly in elevation and partly in central longitudinal section. Fig. 8 is a view of the same 20 as seen partly in elevation and partly in central transverse section on line $x-x$ of Fig. 7.

My invention relates to the class of cuff-pins; and it consists of the novel construction and combination of the several parts hereinabove described, and specifically set forth in the 25 claims.

In Fig. 1 is represented a piece of sheet metal, preferably gold-plated, from which the ornamental or front portion A of the cuff-pin is formed. This piece of sheet metal is cupped up, as shown at $a-a$, preferably in the form of an elongated ellipse or in any other suitable shape, as may be desired. This cupping-up is done by means of a die and plunger in the 30 well-known manner. The sheet of metal is then cut concentrically with said cupped portion, but outside of the edges thereof. In Fig. 1 the hole b represents the outline of the blank which has been cut from the sheet metal, and Fig. 2 represents the blank itself 35 which has been so cut.

In Fig. 2 the concavo-convex ornamental front is designated as A. There are two opposite, long, and broad curved flanges B B 40 and also two short points or projections C C, one at each end of the blank and extending in the line of the major diameter of said elliptical cupped portion. The short curved parallel lines (designated as D D D D in Fig. 45 2) between the ends of the flanges B B and

points C C represent the cut edges of the stock or sheet plate contiguous to the cupped portion a of the blank. The blank is then drawn up on the sides and ends by bending the flanges B B at right angles to their original direction, as shown in Fig. 3 at B', and the points or projections C C are bent up at right angles to their original directions, as shown in Fig. 3 at C' C'. The edges D D D D are left unchanged, and thus constitute recesses with the points or projections C' C' and the flanges B' B', as seen in Figs. 2 and 3, at D' D' D' D'.

E is the lining-plate, having a pin-catch F and two ears G G, all integral. The lining-plate E may have the semicircular notches on its edges, as shown in Fig. 5, to serve as air-holes, as is usual in lining-plates for cuff-pins. These, however, are no part of my invention. The purpose of such air-holes is as follows: 75 Jewelers in finishing cuff-pins subject them to a dipping in acid and to a coloring process. The acid is heated to the boiling temperature. The acid gets between the front and back plates. But for these openings it would be 80 practically impossible to complete the drying-out process when the cuff-pins are put into hot sawdust for that purpose. The ears G G have pivot-holes, and they are spread apart, so as to be divergent, as illustrated in 85 Figs. 5 and 8. The plate E has the two short rounded ends or tips H and H'.

The pin-tongue is shown at I and has a pivot J, which is seated in the pivot-holes of the ears G G when said ears are pinched toward each other to loose contact with the bent end of the pin-tongue I. The lining-plate E from the tip H to the opposite tip H' thereof is precisely of such length as to fit in the cup a with said tips in abutment with 95 the inner surfaces of the bent-up points or projections C' C'. (Shown in Fig. 3.) The side flanges B' B' (shown in Fig. 3) are then rolled over and their edges shut down tightly upon the outer surface of the lining-plate, as 100 seen in Fig. 7, but more plainly in Fig. 8. These rolled-over side portions are designated in Figs. 7 and 8 as B'' B''. The points or projections C' C' are bent down into close contact with the tip ends H and H' of the 105 lining-plate E, as represented at C' C'' in Fig. 7. Thus the lining-plate E is firmly fastened in the concave portion a of the ornamental or front part A of the cuff-pin. The pin-catch F extends up between the adja- 110

cent ends of the rolled flanges B'' B'' and the bent-over point or projection C'', contiguous thereto, and the ears G G extend up between the adjacent ends of the rolled flanges B'' B'' and the bent-over point or projection C'', contiguous thereto. While the pin-catch F and the ears G G make it impossible to provide alongside of them any rolled or bent-over flange, the edges D D D D furnish 10 spaces or recesses between the contiguous ends of the rolled flanges B'' B'' and the points or projections C'' C''. Thus although there is not a continuous roll or bend of the flanges and points the same effect in appearance is produced, and the lining-plate E is securely held in position without the use of solder.

The function of the bent-over point or projection C'' (which is contiguous to the ears 20 G of the lining-plate E) is as follows: If the point or projection C'' (shown in Fig. 7) were omitted from the structure, there would be a liability that when the pin-tongue I is pressed down and turns on the pivot J the right-angled fulcrum-point m of the pin-tongue, which bears with great force upon the part of the lining-plate E beneath it, would exert a sufficient leverage to cause the tip H of said lining-plate to lift away from the 25 ornamental portion or front A of the cuff-pin. To prevent such rise and separation, solder would ordinarily be used; but instead of using solder for this purpose I use the bent-over point or projection C'', as shown in Fig. 30 7, which holds down the point or tip H of the lining-plate E and so prevents it from rising or separating from the ornamental portion or front A of the cuff-pin. The point or projection C'', however, which is contiguous 35 to the pin-catch F, does not serve the function above stated, because there is at that point no harmful leverage on the lining-plate E, caused by the closing of the pin-tongue I; but the use of the point C'' is, 40 first, to make the finish and shape of the two ends of the cuff-pins symmetrical, and, secondly and principally, by making the two ends of the cuff-pin alike the workman may insert the eared portion G of the lining-plate 45 50 E in the cupped depression of the ornamental front A at either end thereof, as may be most convenient for him, and thereupon to bend over into contact therewith that point or projection C' which happens to be contiguous to the tip H on the ear end G of the lining-plate E, and that point or projection C' becomes the one which prevents the said lining-plate from rising by the leverage of the pin-tongue, as described. This construction 55 60 results in a very satisfactory appearance and finish, which with the comparative cheapness of the cuff-pin so produced makes this invention a useful article.

In this invention I do not claim the pin-tongue or lining-plate as my invention, these

being well known and in common use in the art.

I claim as a novel and useful invention and desire to secure by Letters Patent—

1. The improved cuff-pin herein described, 70 consisting of the combination of a lining-plate having earpieces at one end each provided with a pivot-hole and a pin-catch at the opposite end, a pin-tongue engageable with said pin-catch, a pivot on which said pin-tongue is mounted and which extends through said pivot-holes in the earpieces, a cupped-up ornamental front plate in the concave portion of which said lining-plate fits, two integral flanges on opposite sides of said 80 front plate which are rolled over throughout their entire extent into close contact with the outer surface of said lining-plate each of which flanges abuts at one end the pin-catch and at its opposite end one of said earpieces, 85 and two integral points or projections on the opposite ends of said front plate which are bent over into close contact with the tip ends of the lining-plate respectively.

2. The improved cuff-pin herein described, 90 consisting of the combination of a lining-plate having earpieces at one end each provided with a pivot-hole and a pin-catch at the opposite end, a pin-tongue engageable with said pin-catch, a pivot on which the pin-tongue is mounted and which extends through the pivot-holes in the earpieces, a cupped-up ornamental front plate in the concave portion of which said lining-plate fits, two integral points at opposite ends of the 95 front plate bent over into close contact with the ends of the lining-plate so as to abut respectively the pin-catch and the earpieces, and means adapted to secure the lining-plate to the front plates along the portions of the 100 lining-plate which extend between said earpieces and pin-catch.

3. The improved cuff-pin herein described, 105 consisting of a lining-plate having earpieces at one end provided with a pivot-hole and a pin-catch at the opposite end, a pin-tongue engageable with said pin-catch, a pivot on which the pin-tongue is mounted and which extends through the pivot-holes in the earpieces, a cupped-up ornamental front plate 110 having four flanged portions with four intermediate recesses or spaces, which flanged portions are bent over into close contact with the outer surface of the lining-plate the whole being so arranged and combined that the pin-catch and the earpieces extend through said 115 recesses or spaces at the contiguous ends of said flanged portions.

In testimony whereof I affix my signature in presence of two witnesses,

FRANK E. FARNHAM.
